UNITED STATES PATENT OFFICE.

MATTHEW H. LOUGHRIIDGE, OF BOGOTA, NEW JERSEY.

CAB-SIGNAL AND TRAIN-CONTROL SYSTEM.

1,299,595.

Specification of Letters Patent.

Patented Apr. 8, 1919.

Application filed August 24, 1915. Serial No. 47,206.

To all whom it may concern:

Be it known that I, MATTHEW H. LOUGH-
RIDGE, a citizen of the United States, and a
resident of Bogota, county of Bergen, and

5 State of New Jersey, have invented cer-
tain new and useful Improvements in Cab-
Signal and Train-Control Systems, of which
the following is a specification.

This invention relates to cab signals as
10 used on railway trains and to a system for
controlling the speed of said trains, and it
particularly relates to a means for obtain-
ing a variety of effects on the locomotive by
means of devices on the locomotive coacting
15 with devices on the track arranged on either
side equal distances from the center line of
the track.

Among other things this invention has
for its objects means for giving a cab signal
20 on the locomotive showing the state of the
block for a number of blocks ahead of the
train; a system that is operative on each
locomotive as a unit on both single and
double track without regard to which end is
25 leading and without the intervention of any
change-over switching device on the loco-
motive, due to these conditions; a means for
applying a service application of the brak-
ing system under certain combination of
30 cab signals and arrangement of track de-
vices; and a means for applying an emer-
gency application of the braking system un-
der certain combination of signals and ar-
rangement of track devices.

35 This invention has, further, for its ob-
jects a means for controlling the speed of
the train under certain combinations of cab
signals and arrangement of devices on the
track, also a means for controlling the speed
40 of the train independently of the nature of
the signal displayed by the cab signal and
a means for conditionally controlling the
speed of the train according to conditions
on the track.

45 This invention also consists in other fea-
tures of construction and combination of
parts hereinafter described and claimed.

Drawings.

50 This invention is illustrated by the follow-
ing drawings:

Figure 1 track layout of circuits for
double track operation.

Fig. 2 track layout showing arrangement
55 for limited and conditional speed control.

Fig. 3 track layout of circuit for single
track operation.

shoe head in section.

Fig. 10 side view of ramp.

Fig. 11 static speed control device.

As shown in the drawings my invention is
applied with a system in which a normal 70
condition on the locomotive is interrupted at
frequent recurring points on the track and
is renewed or changed according to track
conditions.

In Fig. 5 a closed circuit is normally 75
maintained on the locomotive which controls
the brake valve magnet and cab signal. The
apparatus is designed to interrupt this cir-
cuit each time a locomotive shoe engages a
ramp on the track which will result in an 80
application of the brakes unless current is
collected from the ramp to maintain the in-
terrupted circuit. This arrangement is ex-
tensively used in various ways and is not
part of my invention. 85

The closed circuit includes operating re-
lays 57 and 58, Fig. 5 and can be traced
from battery 41, wire 301, relay 58, wire
303, relay contact 313, wire 304, shoe con-
tact 165, wire 305, shoe contact 306, and 90
wire 302 to battery. When the shoe 11 en-
gages a ramp 14, Fig. 8, it is raised thereby,
moving the lever arm 12, and the cam re-
leasing the plunger 13, which causes the cir-
cuit to open at 165, as hereafter more fully 95
described. This would cause relay 58 to be-
come deenergized and when it is once de-
energized and contact 313 opened it will
not be energized when the circuit is re-
established at 165. This is known as a stick 100
circuit. If, however, when the shoe en-
gages the ramp the latter is energized, then
current will be supplied to wire 308, re-
leasing relay 52 and wire 309 to ground
connection 43 on locomotive. This causes 105
releasing relay 52 to energize picking up
armature 310 and closing a holding circuit
from wire 303 to battery wire 302, thus
maintaining relay 58 energized.

It will be noted from Fig. 5 that two shoes 110

- with accompanying parts are shown. These shoes are placed directly opposite each other on the locomotive and are arranged to engage ramps in exactly the same plane with 5 relation to the track so that the shoe is in position to engage the ramps without regard to which side of the track the ramps may be placed and without regard to which end of the locomotive is running first. It 10 will be found that the circuit of magnet for operating relay 57 is identical with that described for operating relay 58, except that it is controlled by the shoe on the opposite side of the locomotive.
- 15 Fig. 5 represents a locomotive cab signal of the light type, having three different indications: one when both operating relays are energized; one when either one of these relays is energized and the other de- 20 energized and a third indication when both these relays are deenergized. It will be found that a green or clear indication from the lamp G is given when relays 57 and 58 are energized by means of wire 322, contact 314, of relay 57, wire 321, contact 314 of relay 58, wire 302 to battery 41 and wire 301 to common; also a red or stop indication will be displayed from the light marked R when both these relays are deenergized from 25 wire 326, back contact 316 of relay 57, wire 325, back contact 315 of relay 58 and wire 302 to battery, and a yellow or caution indication will be given by the light Y when either one of relays 57 and 58 are deenergized, 30 the other being energized through wire 324, front contact 315 of relay 57 wire 325, back contact 315 of relay 58, and wire 302 to battery, or back contact 315 of relay 57, wire 323, and front contact 315 of relay 35 58 and wire 302 to battery.
- 35 The equivalent effect, mechanically obtained, is illustrated in Fig. 6 in which a signal 17 has a semaphore blade 345 having three positions. One position is obtained 40 when relays 57 and 58 are deenergized as shown, equivalent to the red light R. When say relay 57 is energized, the armature raises vertical rod 348, which raises one side of walking beam 347 which in turn raises rod 45 346 and by a rack and pinion movement causes the semaphore arm to move to the position 345^a. It will be noted that the same effect exactly is obtained should relay 58 be energized raising rod 349 and 57 remain 50 deenergized. This is equivalent to the yellow light indication Y. When both relays 57 and 58 are energized both rods 348 and 349 are raised, moving rod 346 still further upward causing the semaphore to move to 55 position 345^b. This is equivalent to the indication from the green light G. It will be noted that this condition is reversible; that is, if the green light is displayed or if the semaphore is in the position 345^b and either 60 65 one of relays 57 or 58 become deenergized,

the yellow indication or the position 345^a will be displayed and the other indications removed. That is to say; the effects from either shoe acting alone are exactly alike and the effects from both shoes are accumu- 70 lative, and deductive on each other.

Applying the arrangement just described to the track arrangement illustrated in Fig. 1, it will be found that the ramp 481 is placed on one side of the track and the ramp 75 482 on the opposite side of the track, but at the same distance from the center line of the track. The track is divided into blocks A, B, C and D divided by insulated joints 70 on rail 74, into single rail track 80 circuits, fed from the transformers 72 and having the responsive track relays 71 connected by wires 401 and 402 to the track. This is the conventional track circuit, the relay responding to the energy from the 85 transformer when the block is clear and becoming deenergized when a train occupies the block owing to the track transformer being shunted. Stop ramp 481 is energized from transformer 404, through relay contact 411, and wire 450; the other side of the transformer being connected to one of the running rails by wire 401, hence, if the track is clear for one block, ramp 481 will be energized and a circuit will be established 90 from transformer 404 when a shoe encounters this ramp through the circuit of releasing magnets 51 or 52 to ground 43 on the locomotive frame and to the rail 75. Caution ramp 482 is arranged in a similar manner but is designed to control through two blocks instead of one. The circuit of this ramp may be traced from wire 451, relay contact 412, wire 452 and relay contact 411 of the relay for the next succeeding block 105 to transformer 404. This is in accordance with standard practice in which ramp 481 may be regarded as equivalent to a home signal and controls through the first block only, while ramp 482 is equivalent to a distant signal and controls through the first block and the next succeeding block. Visual signals 403 having corresponding indications may be used with this system, if desired, and these signals may be controlled 110 by the same circuit as the ramps, which is indicated by dotted connections to wires 450 and 451.

Applying the arrangement in Fig. 5 or Fig. 6 to the track arrangement in Fig. 1, it 120 is apparent that the shoe on one side of the locomotive will engage ramp 481 and the shoe on the opposite side will engage ramp 482. If the track is clear, the effect from the first shoe engaged will give the equivalent of the caution indication or a yellow light and the effect from the next shoe added to this will give a clear signal or a green light, which condition would be maintained until a deenergized ramp was encountered; when 130

the indication would be changed from a clear to a caution signal and this condition would be maintained until another energized ramp on the same side of the track was encountered, which would restore the clear signal again or until a deenergized ramp on the opposite side of the track was encountered, which would change the caution to a stop signal or red light—a condition that would be maintained until another energized ramp was encountered and the caution signal renewed.

It will be noted that the indication given by the caution ramp includes the section of track governed by the stop ramp, plus an additional section. The caution ramp can therefore never become energized unless the stop ramp is energized, although of course, the stop ramp can be energized when the caution ramp is deenergized. This arrangement, therefore, makes the effects on the track obtained from the caution ramp accumulative on the effects obtained from the stop ramp, so that no irregularity can arise in operation. As already explained, the effects obtained from each shoe on either side of the track are exactly alike and these effects are accumulative on each other. It is thus apparent that since the shoes are not used for a specific purpose, it makes no difference which engages the stop ramp and which engages the caution ramp; hence, the system is equally effective on the locomotive without regard to which end may be leading and also for single track operation, where train movements are in both directions, and where a train may, at any time, change its direction of running. This is an important feature of my invention, as hitherto this object could only be accomplished either by placing the ramps on different horizontal planes at the side of the track, and by using each shoe for a specific purpose, as for instance, one shoe being arranged to give a caution signal and the other shoe arranged to give a stop signal, and when the locomotive changed its direction of running, it became necessary to use a synchronizing device associated with the reverse lever or otherwise to make the circuits properly function.

The arrangement in Fig. 1 is applied to what is known as single rail track circuits, that is, only one of the running rails are provided with insulated joints, the other rail being continuous and without insulated joints. This rail is therefore used as a return conductor from each of the transformers through the locomotive to the ramp. Where desired, however, the energy may be applied to the caution ramp locally by the use of a line relay, in a manner well known to the art.

The arrangements so far described relate to applications where traffic is always in the same direction, as in double track operation.

To apply the system for use on single track, certain modifications are necessary the principle of which is to provide a means of placing the home and distant ramps outside of the block to be entered, when running in either direction. An arrangement of this kind is illustrated in Fig. 3, in which the track is divided into blocks A, B, C, D, E, and F. The blocks A, C and E are short sections of track, opposite the home and distant ramps, and the circuits are so arranged that this section is included with the preceding block section for each direction of running; for instance, section C is included as part of block B when traffic is running from A toward F and is included with section D when traffic is from F toward A.

According to standard practice for single track operation, direction relays are employed which establish conditions suitable for the direction of running desired. Direction relays 78 when energized, establish a running direction from A toward F and direction relays 77 when energized, establish a running direction from F toward A. It will be noted that each relay is controlled by the succeeding corresponding relay, as for instance, relay 78 is controlled by wire 482, and contact 417 of relay 78 at the next location, wire 481 to battery 409 and wire 455 common return. Relay 77 is controlled by wire 483 to contact 417 of relay 77 at the next location to battery 409 and wire 455 common return. At the last location relay 78 is controlled by wire 486, switch 490, wire 487, back contact 417 of relay 77 to battery 409; and relay 77 at the last block is controlled by wire 484 switch 490, wire 485 and back contact 417 of relay 78. By this arrangement only one set of direction relays can be energized at any one time.

The home and the distant ramps are first controlled by the direction relays and then by the regular controlled circuits. The circuit for the home ramp can be traced from wire 450, contact 418, of relay 78, wire 471, contact 411 of relay 71, wire 465, contact 411, of relay 71, at the succeeding short block section. Hence, the home ramp includes control over a long and short track section. The distant ramp 432 controlled by wire 451, contact 419, of relay 78, wire 470, contact 412, of relay 71, wire 452, contact 412 of relay 71 at the next succeeding short block section, wire 472, contact 420, of relay 78, to wire 450, where it picks up the same control as the next succeeding home ramp, in accordance with standard practice. In the opposite direction from F to A, the direction relays 77 are energized and 78 deenergized, circuit from the home ramp can be traced from wire 450, contact 418 of relay 77, wire 466, relay contact 413, wire 468, and contact 413, of track relay for the long and short track sections, to battery 407. The distant ramp is controlled by wire 451, con-

tact 419 of relay 77, wire 467, relay contact 414, wire 469, relay contact 414, of track relay 71 for the long and short track section, and wire 466, where it picks up the control 5 of the home ramp for the next succeeding section, and so on.

In the modified arrangement for single track operation shown in Fig. 4, instead of using short independent track circuits for 10 the portion of track opposite the ramps, these sections A, C and E are transferred by the operation of the direction relays and included in the adjacent block to the direction in which the train is approaching. For instance, when traffic is from A to F, section C 15 is included as part of block B and when traffic is in the opposite direction this section is included with block D, the arrangement being such as to insure that the ramps will 20 be encountered before the block over which they govern is entered.

This is secured by shunting the joint 70^a and arranging the track connections accordingly when traffic is from A to F and by 25 shunting the joint 70^b when traffic is from F toward A. This is accomplished by wire 496 back contact 418 of relay 77 and wire 495, which shunts joint 70^a. Track battery 30 73 is connected by wire 497, back contact 417 of relay 77, wire 494, to track 74 adjacent to joint 70^b. This track battery, therefore, feeds the track relay 71 for track sections B and C. Track relay 71 for section D connects to rail 75 by wire 401 and to rail 74 35 through wire 402, front contact 417 of relay 78 and wire 402^a, this condition being maintained at each location.

When traffic is established in the opposite direction, the track relay for section D is 40 connected to section C and joint 70^b is shunted. The circuits for this relay may be traced from wire 402, back contact 418, of relay 78, wire 495 to rail 74. The joint 70^b is shunted by connection 402^a, back contact 45 417, of relay 78 and wire 494, the shunt on joint 70^a being removed when relay 77 is energized and the track battery 73 is connected to section B through front contact 417 of relay 77.

50 In this figure the wire 452 for controlling the distant ramp 432 has been separated into two wires which will be more fully explained in connection with the speed control system hereafter. Wire 452 controls the distant ramp for traffic from A toward F and wire 452^a controls for traffic from F toward A. These circuits may be traced from wire 451, front contact 419 of relay 78, wire 470, front contact 412, of relay 71, wire 452, front contact 422, of relay 78, and wire 471, where it picks up the control for the home ramp at the next location. A resistance 379^a connecting to battery 407 and included in the circuit 55 of the home ramp, is shown in this figure.

60 On referring to Fig. 1 and Fig. 2 it will

be noted that the home ramps 431 and the distant ramps 432 are staggered in relation to each other in their location on the track, except the ramps in section D where they are placed opposite. Since the shoes on the 70 locomotive are placed opposite each other I utilize the difference in effects obtained when the ramps are staggered and when they are opposite to establish different purposes. The staggered arrangement I have designed 75 to apply a service application of the brakes when the block is obstructed, and the arrangement with the ramps opposite I have designed to apply an emergency application of the brakes. The former is used, at what 80 might be termed permissive block signals, while the latter is applied at positive stop signals, as for instance, at signals which are protecting switches.

Referring to Fig. 5, 61, is the service brake 85 magnet, applied to the brake pipe 250, and 62 is the emergency brake magnet. The circuit of magnet 61 can be traced from battery wire 301, wire 340, contact 338 of magnet 61, wire 334, front contact 317 of relay 57, wire 333 front contact 317 of relay 58, and wire 302 to battery. When, therefore, either of these relays are deenergized, the circuit of this magnet is opened, opening contact 338 which forms a stick circuit, so 90 that it does not restore again until the operation of the hand time release 26, which after a definite time interval applies battery to wire 340 from wire 302; thus when a deenergized ramp is encountered service application 95 of the brakes is obtained, which can only be released after the lapse of a given time interval. This operation is modified by the speed control system to be described later.

100 The circuit of the emergency brake magnet 62 can be traced from wire 336, contact 318, of relay 58, to battery wire 302, also from contact 318 of relay 57, to battery wire 302. This magnet is, therefore, connected in 105 multiple circuit with the front contacts of both these relays and hence will not be deenergized unless they are both deenergized. Further, this circuit is also connected in multiple with contacts 164 of each shoe 110 to wire 305 and to battery wire 302 through contact 306; hence, when either shoe operates alone this magnet is not affected and it is not affected when both shoes act together if either one encounters an energized ramp, 115 but it is effective when both shoes simultaneously encounter deenergized ramps, such as would occur in section D, Fig. 1, if the block were occupied. This magnet also has a stick circuit through contact 339 which is 120 opened when it is deenergized and must be manually restored by the push button 25, making contact between wires 341 and battery wires 302.

125 While this application is shown as applied 130

to a staggered arrangement of ramps on the track and an opposite arrangement of shoes on the car I wish it to be particularly understood that these conditions can be reversed, that is, all the ramps on the track may be placed directly opposite, and the locomotive or car can be provided with a set of shoes placed in staggered relation to each other; to obtain the effects desired as a car condition instead of a track condition, an occasion for a use of this kind might arise where it was desired to change the function of the car equipment when it is applied to different uses.

When an arrangement of this kind is applied on multiple unit trains, it may, at times, become desirable to render the system inoperative on intermediate cars or locomotives and I have therefore provided a cut out arrangement, as shown in Fig. 7, which suspends the operation of the system, only by the concurrent action of two men. Relay 60, as shown in Fig. 5, is applied to hold valve magnets 61 and 62 energized. This magnet can only be picked up when levers 381 and 382 are operated simultaneously. These levers are placed at opposite ends of the car or far enough apart to prevent their operation by one person and are biased so that they will remain either in the off position or in the release position by spring 383, but they cannot be left in an intermediate position.

When these levers are moved in the direction of the arrow, contact 391 engages rim 389^a of contact piece 389. This supplies current from battery 41 through wire 301 contact 391 wire 385, contact 391 of other lever, contact piece 389, wire 388, to relay 60 and wire 302 to battery. This energizes the relay and in order to maintain it energized the levers must complete their stroke so that contact 392 connects with 390. This supplies battery to wire 386 and wire 387, which maintains the holding circuit for the relay, as long as the levers are in this position. When the levers are reversed, the contact piece 391 moves over the opposite side of contact 389^a which is insulated and does not form a circuit; hence the movement of either lever will deenergize relay 60 and cut the system into operation, that is, the system may be cut into operation by the efforts of one man but it requires the concurrent action of two men and thus divided responsibility for rendering the system inoperative. The movement of the levers 381 and 382 may be designed to cover up the indications by a disk displayed by the cab signal when the system is released.

In Fig. 5 separate releasing relays 51 and 52 are used to respond to the current from the ramp, these relays in turn closing the holding circuit of the operating relays 57 and 58. In Fig. 5 alternating current relays

are used, this arrangement being designed for use with Fig. 1, which uses alternating current for energizing the ramps. As a source of alternating current is not readily available on a locomotive and as it would be quite impossible to get the same phase relation between the current collected from the ramp and from that on the car, the use of a separate relay is imperative, with alternating current. The system may, however, be applied with direct current, without the use of this relay, the operating relays 57 and 58 being connected directly to the shoe.

The construction of the shoe can be understood by referring to Figs. 8 and 9. The pedestal 101 is clamped against the equalizer 105 of the pony truck 106 of the locomotive by means of the clamp 104 and is insulated therefrom by a sheet of fiber 103. This clamp also supports the frame 102 by an adjustable rack. The shoe 11 is pivoted at 117 in the other extremity of the bracket 101 and consists of two rollers 114 pivoted on bearing 115, in the shoe head 116. The weight of this shoe tends normally to hold the stop screw 119 against the stop 118 of the bracket. This may be further assisted by a spring, which is not shown in diagram.

On the same axis 117 is a lever arm 12, which responds to the movement of the shoe 11 by means of the adjusting screws 126, and 128 engaging part of this lever arm thereby causing it to move rigidly with the shoe. This lever arm has a section of insulation 131, clamped by the bracket 130, so that the part of the shoe engaging the ramp is entirely insulated from the rest of the mechanism. The upper end of the shoe is cam shaped having two sections, a lower section 133 and a raised section 132. Engaging this cam is the roller 135 at the end of the plunger 130, which moves vertically in the bearings 160, and is normally held in tension downward by the spring 161 acting against the collar 162. The lever arm 125 increases the effect obtained from raising the shoe when it engages the ramp. This moves the raised portion of the cam 132 from beneath the roller 135 allowing it to rest on the lower cam 133. This always insures a constant movement of the plunger 13 and provides for any irregularities in the engaging surface of the ramp, besides bringing the plunger 13 into the opposite position on a fraction of the full movement of the shoe correspondingly increasing the factor of safety.

The ramp as shown is supported by a sleeper 109 securely fastened to ties 108 outside the running rail 107. On this sleeper is placed a section of T iron 110 constructed in a way that is practically as substantial as the track itself. Bolted to the T iron are two engaging plates 112 and 113, which extend somewhat above the T iron thus leaving a groove in the top of the ramp. A side ele-

vation of these plates is shown in Fig. 10. Two rollers are provided on the shoe, the first one for the purpose of brightening the surface of the ramp and the second one to make the electrical contact. Another advantage in raising the plates 112 and 113 above the T rail, is that this forms a good guide as to the amount of wear which these engaging plates have received and forms a guide as to when they should be replaced.

10 A shoe of this kind while it may be thoroughly protected by shields may accidentally be torn off or misplaced. If this should happen, the counterweighting effect on the lever 15 arm 12 would be withdrawn with the result that the spring 127 would move this arm into the operative position, thus effecting the control of the apparatus. As a further assistance in this direction, the center line 20 of the plunger 13 is off centered on the axis 117 so that the downward pressure of the spring 161 tends to move this arm into this position; besides being assisted by a greater weight at 132.

25 The safety of a system of this kind depends upon the movement of the shoe. If the shoe fails to move, or if it fails to move a sufficient distance a normally clear signal already established would be continued 30 without regard to the conditions of the block about to be entered. It is very important, therefore, to insure proper movement of the shoe and some means for detecting improper movements. One means to this end is shown 35 in Fig. 9, designed to guard against excessive wear on the rollers 114. When these rollers are worn to such an extent that the soft metal cap 155 is brought into engagement with the ramp, it quickly becomes worn 40 through, releasing the plunger 156 which under the tension of spring 157 opens the circuit 306 in the case 158. This circuit controls the battery current for the shoe and therefore if it becomes opened, it has the 45 same effect as a deenergized shoe. The same results will occur if the shoe is torn off and misplaced.

50 Failures are liable to occur due to excessive wear of the ramp. I have provided a detector which will sound an audible signal on a locomotive when a shoe at any time makes an incomplete movement. This is secured by the slide valve 143 in the chamber 142 operated by the lever arm 12 through 55 the connection 141. When the lever arm makes a complete movement, the space 153 in valve 143 moves quickly over the opening in pipe 146 which does not affect the whistle 147, but when an incomplete movement is 60 made the air supply from pipe 231 to the port 153 of the slide valve enters pipe 146 and sounds the whistle 147, thus bringing attention to the incomplete movement of the shoe.

65 When a clear signal is received by this

system it remains indefinitely as a clear signal although conditions may in the interval have changed before the train passes over the block. I have therefore provided a time limit indicator, showing how long, under normal conditions a signal may be regarded as effective and of full importance. This I secure by the indicator 151 having a pointer 152 connected by a pipe 150 with the air reservoir 149 and pipe 148 with 75 valve 142. When the shoe is raised pipe 148 communicates with port opening 153, allowing air to pass from the pipe 231 into the reservoir 149 and moving the indicator 152 to the raised position. As soon as the 80 shoe is disengaged from the ramp and the lever arm assumes the normal position, pipe 148 is connected with chamber 144^a and the air pressure in reservoir 149 is slowly released through the opening 144 and regulated by the ball valve 145 until the pressure is released from chamber 149, which allows the indicator to move back to the zero position. The time consumed in doing this represents the time in which the signal may be 90 regarded as fully effective. By the use of the circuit controller 152^a operated by the indicator 152 this may be arranged to effect control of part of the circuits of the cab signal system. It will be noted that when 95 the speed of a train is high, it will pass rapidly over the ramps and while there will be less time to build up a high air pressure in chamber 149 there will be also less time to exhaust this air pressure until another ramp is encountered. This condition is conversely true when the speed is low.

Speed control.

100 The system of speed control disclosed in this invention consists in the use of a device on the locomotive, having a definite time interval and of ramps on the track having a characteristic co-acting with the speed control device on the car in such a way as to 105 control the speed according to track conditions.

110 The speed control device is illustrated in Fig. 11 and in application at 115 Fig. 5. This device consists of a horizontal cylinder with different chambers and as shown with three vertical cylinders, the mechanism being supported by the frame 158. Air pressure is applied to pipe 231 from the main 120 reservoir of the air braking system of the locomotive and through the passage 232, chamber 233 and passage 235 connects with cylinder 204. The other end of passage 232 connects with cylinder 203. It will be observed 125 that since cylinder 203 has the piston 211 rigidly connected with the piston 212 the former being of smaller diameter, that there will be a greater expansion in cylinder 204 by the movement of the piston; hence, 130

the air pressure will drive the piston to the left. This will force the oil in cylinder 202 through the ball valve 241 into cylinder 201 forcing piston 210 upward; thereby, raising 5 piston rod 218 and closing circuit between contacts 168^a and 168^b carried on the insulated plate 166 by the contact 168.

If the shoe encounters a ramp, the cam is withdrawn from roller 135, plunger 13 is 10 forced downward by spring 161. This in turn moves the valve stem downward, causing the valve 240 to suddenly exhaust cylinder 204 through the large exhaust port 239. Also closing the passage between chambers 15 233 and 235 by valve 238 and opening passage between chambers 233 and 236. The sudden release of the air pressure in cylinder 204 enables the air in the cylinder 203 to expand by forcing the piston to the right, 20 which it does quickly. This, in turn, draws the oil from cylinder 201 and spring 219 moves piston 210 downward opening contact between 168^a and 168^b and closing contacts 168^c and 168^d. The air pressure from 25 pipe 231 is now in communication with passage 236^a through chamber 233 and 236 and by means of the spring seated valve 237 and regulated ports it is admitted at a comparatively slow rate into cylinder 205 and 30 when the air pressure in this cylinder is sufficiently built up it will move the pistons 213 and 211 and 212 which are all connected on the shaft 220 to the left again as shown, thus forcing the oil back into cylinder 201 35 and closing contacts 168^a and 168^b again. The time consumed in building up the air pressure in cylinder 205 so as to drive the piston back into the normal position represents the time interval of the speed control 40 device. This should take place when the valve 238 is in the down position, that is, during the time that the shoe engages the ramp. This time is, of course, dependent upon the speed of the train and the length 45 of the ramp; as the length of the ramp is a track condition and therefore may be variable, the speed of the train can be controlled according to track conditions.

By referring to the application in Fig. 50 5, it will be noted that the effects from speed control circuit controller 168 are rendered inoperative when plunger 13 is down; that is during the transit of the shoe over the ramp. This is secured by the back contacts 55 165 closing the circuits between wires 335 and 334 when the plunger is down; hence, although the quick movement of the piston 210 opens the speed control circuit 168, if it is driven back to the normal position again before a shoe leaves the ramp, the 60 circuit of the brake valve magnet 61 is not interrupted and on the other hand if it fails to drive the piston back to the normal position before the shoe leaves the ramp then the 65 circuit of this magnet will be opened and

can only be restored by the hand time release 26; that is to say that if the speed of the train in passing over the ramp is such that the speed control device is not restored to the normal position, then the service 70 brake magnet is released to apply the brakes. On the other hand, if the train moves slowly over the ramp this circuit will be restored and the control will remain ineffective. It should be observed that brake 75 magnet 61 in addition to being controlled in series by operating relays 57 and 58 is also controlled in series by the speed control circuit controller 168 on both shoes from wire 334, contact 168, wire 335, contact 168 of 80 other shoe to battery wire 302.

It has been explained that the time interval of the speed control device depends upon the time necessary to raise the pressure in cylinder 205 to operate the piston 213. This 85 also depends upon the size of chamber 205; therefore, if the size of this chamber is varied, it is possible to vary the speed allowable with any particular arrangement of ramps. This may be desirable in certain 90 cases, where, for instance, a locomotive may be used in passenger service and a comparatively high speed is desirable and at other times used in freight service where a low speed only is safe. I have provided for 95 this condition by varying the size of chamber 205 through the movement of piston 214 by the adjusting screw 225 which varies the size of chamber 206, a graduated indicator 226 may be used in connection with 100 piston 214 showing the speed at which the device is set to function.

Other reasons may make it desirable to regulate the allowable speed as a car condition, for instance, it may be desirable to 105 have a different speed for a loaded and an empty car, or again it may be desirable to limit the speed when the pressure in the air braking system becomes reduced. The latter condition is obtained by the use of cylinder 209 in which the air brake pressure from pipe 231 acts upon piston 217 and against spring 224 to which it is connected by rod 223 and piston 216. Under normal conditions as the braking pressure in the train line 231 is varied, the position of piston 217 is correspondingly raised or lowered. This in turn varies the size of chamber 208, which communicates with chamber 205 by the passage 244 and therefore varies the time interval of the speed control device decreasing this interval as the braking pressure is increased. When piston 213 is moved to the normal position the pressure in chamber 205 is released to atmosphere through opening 243.

It will be noted that the end of passage 232 opening into cylinder 203 has an extended orifice 234 which when the piston is moved to the right, is covered by the ex- 130

tension 234^a on piston 211, thus shutting off the air pressure to cylinder 203 and obtaining a more effective operation in restoring the piston through chamber 205.

- 5 When the air pressure is released in cylinder 204, it is also released in cylinder 207 through the passage 242. This allows piston 215 to move downward under the action of spring 222, opening circuit between contacts 169^a and 169^b carried on the insulated plate 167 through the contact 169. Now if the piston 212 when moved to the right occupies the position shown dotted, does not restore to the normal position within a certain time interval, the air pressure in cylinder 203 which now communicates with cylinder 207 will raise piston 215 and thereby complete the circuit of the alarm bell 170 from the battery 171, as shown by the dotted lines through the circuit controller 168 and the contacts 168^c, 168^d, thus giving a warning that the speed is excessive. On the other hand, if the piston is moved back the circuit 168^c, 168^d will be opened before the circuit 169^a, 169^b is closed and no alarm will be given.

It will be noted that the speed control device functions when each ramp is encountered to control the speed of a train and it

- 30 functions by withdrawing the cam from beneath the roller 135, so that the speed of the train is controlled at each ramp according to track conditions. Attention is also drawn to the fact that the air pressure in the setting cylinder 203 comes from the same source as the air pressure in the restraining cylinder 204 so that any variation in the positive effect is correspondingly varied in the negative effect without changing the time interval 40 of the device. If the air pressure fails altogether, then the spring 219 will force the piston 211 to the right and thus open the speed control circuit. A restraining influence on the restoring effect may be obtained 45 by regulating the opening 241 of the ball valve communicating with cylinder 201. This might be desirable, for instance, in cold weather when the oil becomes more viscous to increase size of this opening. After a 50 ramp has been engaged and the valve stem 13 is restored to the normal position, the exhaust port 239 is closed and chamber 204 is supplied with air through the passage 235 from pipe 231. The restoring pressure 55 in cylinder 205 is being retained by the spring seated valve 237 until the opening 243 is uncovered.

- 60 The circuit controller operated by the lever arm 12 is placed below the speed control device and carries insulated contact pieces 164, 165, making electrical contacts between 164^a and 164^b and 165^a and 165^b when raised and making contact with 164^c and 164^d and 165^c and 165^d when released.

These contacts are mounted on the insulated 65 base 159.

The application of the speed control system will be understood by referring to the track lay out diagrams. The home and distant ramps are of such a length as will permit the maximum allowable speed, and spaced at intervals in each block, are a row of ramps exactly like the other ramps except that each are successively shorter in length as in Fig. 1, corresponding to the allowable speed at their respective locations. These ramps are connected to wire 452, which has the same control as the home ramp for the next succeeding block. If, therefore, in Fig. 1, a train occupies block B and another train attempts to enter block A, the distant ramp 432 will be deenergized giving a caution signal. Also ramps 434, 435 and 436 will be deenergized. This train, therefore, on passing ramp 434 must reduce speed 85 corresponding to length of that ramp and must reduce speed still further on passing ramp 435 and still further on passing ramp 436, each of which are successively shorter. This in effect would reduce the speed of a 90 train to zero, before it entered block B, which was obstructed by another train.

With this arrangement it will be noted that should block B subsequently be cleared after the train had entered block A and received caution signal from ramp 432 then wire 452 would become energized and the next speed control ramp encountered would give a clear signal.

From the wiring of the locomotive apparatus, Fig. 5, it will be observed that the circuit of brake magnet 61 is energized when control relays 57 and 58 are energized and brake magnet 62 is energized when either of these relays are energized. As these relays 105 remain energized when the shoes encounter energized ramps it is apparent that the speed of a train entering a clear block is not controlled by any ramp whatever its length may be if it is energized.

110 It is conversely true that if a train should enter a block under a clear signal and the block ahead subsequently becomes obstructed, the next ramp encountered would communicate a caution signal to the train and make the speed control effective.

115 In connection with the single track arrangement shown in Fig. 3, it is not possible to arrange one set of ramps for traffic in both directions so that they shall successively become shorter as a train moves through the block. In this case, the minimum speed ramp is placed at the center of a block and the ramps approaching it in either direction 120 434 and 434^a are higher speed ramps. This 125 reduces the speed of a train until it gets half way through the block, but does not insure against an excessive speed after this

point is reached. In the modified arrangement, shown in Fig. 4, this condition is overcome by the use of two sets of ramps on the same plane, one for each direction of running. The circuit controlling these ramps is so arranged that the ramps for the opposite direction are always energized and the ramps for the running direction are controlled by the block system. Also these ramps are placed comparatively close together so that after an energized ramp is encountered a block controlled ramp is immediately encountered thereafter. The result is to momentarily give a clear signal from the energized ramp and immediately thereafter subject the train to speed control from the speed control ramps. If the block is clear, conditions will, of course, be normal, as both sets of ramps will be energized.

20 The ramps for the running direction A toward F, 434, 435 and 436 are connected to wire 452 through contact 422 of relay 78 and wire 471 where they pick up the control for the home ramp 431 of the next block.

25 The speed control ramps 434^a 435^a and 436^a for the opposite direction are connected to wire 452^a and through relay contact 421 of relay 78 to battery 407 by wire 498. This permanently energizes the ramps. It will be observed, however, that ramp 435 immediately follows ramp 435^a, ramp 436 immediately follows ramps 434^a. That is to say, the energized ramps are always encountered before the block controlled ramps.

30 35 When traffic conditions are established in the opposite direction from F toward A it will be found that wire 452 is permanently energized through contact 422 of relay 77 connecting to battery wire 498 and that wire 452^a is disconnected from battery 498 through contact 421 of relay 78, which is now opened and by means of contact 421 of relay 77 connects to wire 466, which picks up the circuit of the home controlled ramp 431 of the next succeeding block.

40 45 It is sometimes desirable to control the speed of a train owing to some physical condition of the track other than an obstruction from the block, as for instance, obtaining a limited speed in tunnels and on curves and it is also desirable to conditionally control the speed of trains when the track is set for a turn out and without regard to the state of the block. These conditions may be obtained with this system by the arrangement in Fig. 2. Assuming that section P represents a portion of track over which it is desired to obtain limited speed, which limited speed, however, may be varied. I 50 55 secure this condition by the use of limited speed control ramps 438, 439 and 440. These ramps are of such a length or have a characteristic that will control the train if the allowable speed at their respective locations is exceeded. These ramps are "dead," 65 that is, they are not connected to any source of energy and are insulated; therefore when encountered, they give the effect of a caution signal and at the same time render the speed control effective throughout the section in which it is desired to secure limited speed. Immediately following each of these ramps are located the regular speed control ramps of the block system so that if the block is clear, the clear signal is restored 70 when these ramps are encountered and after the speed control has become effective. On the other hand, if a train enters the block under a caution signal, its speed will be subordinated to the control of the shorter regular speed control ramps. These ramps require a lower speed than the limited speed control ramps.

75 80 At a turn out, as for instance, in block D it is desirable to insure that a limited speed shall be observed when the switch is set for the turn outs. This is secured by the limited speed control ramps 442 and 443 connected by wire 462 and circuit controller 449 operated by rod 448 connected with the switch mechanism, wire 463, contact 411, of relay 71 to battery. When the switch is set for the straight track, as shown wire 462 is energized, having the same control as wire 452, hence, these limited speed control ramps do not change the conditions on the car, for if the block is clear, a clear signal is maintained and if the block is obstructed a caution signal is maintained, but the speed of a train is subordinated to the lower speed allowable by the regular speed control ramps. On the other hand, if the switch is set for the turn out, and the track is clear, circuit controller 449 is opened and ramps 442, 443 are "dead" and therefore 90 95 become effective to control the speed of a train in a manner similar to the limited speed control ramps already described.

100 105 Claims:

110 1. In combination, a railway track, a vehicle moving thereon, a ramp on said track having the character of an inclined plane, a shoe carried by said vehicle and engaging said ramp, a train controlling mechanism, said shoe consisting of a plurality of members pivoted on the same axis, said members 115 adjustably connected and operating said train controlling mechanism.

120 2. In combination, a railway track, a vehicle moving thereon, a ramp on said track having the character of an inclined plane, a train controlling mechanism, a shoe carried by said vehicle and engaging said ramp, said shoe consisting of a plurality of members pivoted on the same axis, said members 125 being adjustably connected, a cam connected with said shoe and operating said train controlling mechanism.

3. In combination, a railway track, a vehicle moving thereon, a ramp on said track having the character of an inclined plane, a train controlling mechanism, a shoe carried by said vehicle engaging said ramp and moved thereby, said shoe consisting of a lever arm fulcrumed to increase the effect from said ramp and a cam connected with said shoe and operating said train controlling mechanism.
4. In combination, a railway track, a vehicle moving thereon, a ramp on said track having the character of an inclined plane, a train controlling mechanism, a shoe carried by said vehicle and engaging said ramp, said shoe consisting of a lever arm having a horizontal and a vertical member, the vertical member being the longer and having a cam at its extremity to operate said train controlling mechanism.
5. In combination, a railway track, a vehicle moving thereon, a ramp on said track, a train controlling mechanism, a shoe carried by said vehicle and moved by said ramp, said shoe consisting of a lever arm fulcrumed to increase the effect from said ramp and means operated by said shoe for imparting a uniform effect to said train controlling mechanism irrespective of irregularities in the effects from said ramps.
6. In combination, a railway track, a vehicle moving thereon, a ramp on said track, a train controlling mechanism, including a plunger, a shoe carried by said vehicle and moved by said ramp, said shoe consisting of a lever arm fulcrumed to increase the effect from said ramp and arranged to operate said plunger and means securing a uniform motion of said plunger irrespective of irregularities in the effects from said ramps.
7. In combination, a railway track, a vehicle moving thereon, a ramp on said track, a train controlling mechanism, a shoe carried by said vehicle and moved by said ramp, said shoe consisting of a lever arm having a cam operating said train controlling mechanism and means effecting said operation when said cam is moved from a higher to a lower effective position.
8. In combination, a railway track, a vehicle moving thereon, a ramp on said track, a train controlling mechanism, a shoe carried by said vehicle and moved by said ramp, said shoe including an arm with a cam at its extremity and operating said train controlling mechanism, said mechanism being arranged to retard the progress of said train when said cam operates said mechanism in its lower position.
9. In combination, a railway track, a vehicle moving thereon, a ramp on said track, a train controlling mechanism including a plunger, a shoe carried by said vehicle and moved by said ramp, said shoe including an arm with a cam at its extremity, said cam moving said plunger, the action of said plunger falling in a plane outside the pivot of said arm, thereby tending to move said cam from a higher to a lower effective position.
10. In combination, a railway track, a vehicle moving thereon, a ramp on said track, a train controlling mechanism, a shoe carried by said vehicle and moved by said ramp, said shoe consisting of a heavy horizontal arm and a light vertical arm, said vertical arm operating said train controlling mechanism and biased to a position retarding the progress of said train, said vertical arm responding to the movement of said horizontal arm.
11. In combination, a railway track, a vehicle moving thereon, a ramp on said track, a train controlling mechanism, a shoe carried by said vehicle, said shoe consisting of a horizontal arm engaging said ramp and a vertical arm operating said train controlling mechanism, means bringing said vertical arm into position to retard the progress of said train when said horizontal arm is removed.
12. In combination, a railway track, a vehicle moving thereon, a ramp on said track, a train controlling mechanism, a shoe carried by said vehicle, said shoe consisting of two members, one member biased to effect said train controlling mechanism and the other biased to prevent said control, the bias of the latter being overcome by said ramps.
13. In combination, a railway track, a vehicle moving thereon, a ramp on said track, a train controlling mechanism, a shoe carried by said vehicle, said shoe consisting of two members separately mounted and adjustably connected, one member operating said train controlling mechanism, the other member engaging said ramp, said adjustment taking up the wear between said shoe and ramp.
14. In combination, a railway track, a vehicle moving thereon, a ramp on said track, a train controlling mechanism, a shoe carried by said vehicle, said shoe designed to make electrical contact with said ramp and to be displaced thereby to operate said train controlling mechanism, said contact being made through twin rollers placed in tandem.
15. In combination, a railway track, a vehicle moving thereon, a ramp on said track, a train controlling mechanism, a shoe carried by said vehicle and designed to make electrical contact with said ramp, said shoe having a plurality of rollers, said ramp consisting of a plurality of longitudinal ridges engaging said rollers.
16. In combination, a railway track, a vehicle moving thereon, a ramp on said track, a shoe carried by said vehicle and

- designed to make electrical contact with said ramp, said shoe having a plurality of rollers, said ramp consisting of a plurality of ridges which are detachable, said ridges engaging 5 said rollers.
17. In combination, a railway track, a vehicle moving thereon, a ramp on said track, a shoe carried by said vehicle, said ramp consisting of a section of iron having a vertical rib, plates secured to said rib and rising in a higher vertical plane, said shoe making electrical contact with said ramp.
18. In combination, a railway track, a vehicle moving thereon, a ramp on said track, a train controlling mechanism having a main circuit, a shoe carried by said vehicle and including a plurality of rollers engaging said ramp and means affecting said main 10 circuit when said rollers are worn to a predetermined extent.
19. In combination, a railway track, a vehicle, ramps on said track, a shoe carried by said vehicle and including a circuit controller, rollers engaging said ramps and a plunger operating said circuit controller, said plunger extending below the axis of 25 said rollers.
20. In combination, a railway track, a vehicle moving thereon, ramps on said track, a train controlling mechanism, a detector mechanism, a shoe carried by said vehicle and displaced by said ramps for operating 30 said train controlling mechanism, means connected with said shoe and operating said detector mechanism for detecting when said displacement is below normal.
21. In combination, a railway track, a vehicle moving thereon, ramps on said track, a train controlling mechanism, a shoe carried by said vehicle and displaced by said ramps for operating said train controlling mechanism, said shoe consisting of a lever fulcrumed to increase the effects from 35 said ramps, a plunger connected to the end of said lever and means controlled by said plunger for detecting when the displacement of said shoe is below normal.
22. In combination, a railway track, a vehicle moving thereon, ramps on said track, a shoe carried by said vehicle and displaced by said ramps, a valve, a source of energy controlled by said valve, means for operating 40 said valve by the movement of said shoe and means for giving a signal when said displacement is below normal.
23. In combination, a railway track, a vehicle moving thereon, ramps on said track, a shoe carried by said vehicle and engaging 45 said ramps, said shoe consisting of a lever arm fulcrumed to increase the effects from said ramps, a timing device having means for registering the time said shoe is in engagement with said ramps.
24. In combination, a railway track, a vehicle moving thereon, ramps on said track, a shoe carried by said vehicle and engaging 50 said ramps, a cab signal giving a fixed indication and responding to said ramps, a timing device operated by said shoe and arranged to indicate the time said fixed indication shall be effective.
25. In combination, a railway track, a vehicle moving thereon, ramps on said track, a shoe carried by said vehicle and engaging 55 said ramps, a cab signal giving a fixed indication and responding to said ramps, a timing device operated by said shoe and means including said timing device for limiting the time said fixed indication shall 60 be effective, said means varying with the speed of said vehicle.
26. In combination, a railway track, a vehicle moving thereon, ramps on said track, a shoe carried by said vehicle and engaging 65 said ramps, a cab signal giving a fixed indication and responding to said ramps, a timing device operated by said shoe, and means including said timing device for limiting the time said fixed indication shall 70 be effective, said means varying with the speed of said vehicle.
27. In combination, a railway track, a vehicle moving thereon, ramps on said track, a shoe carried by said vehicle and engaging 75 said ramps, a cab signal giving a fixed indication and responding to said ramps, a timing device controlling said signal and consisting of an air supply, a valve and a reservoir, said valve operated by said shoe, and 80 means including said valve for admitting air to said reservoir when said shoe engages a ramp and means for gradually exhausting said reservoir when said shoe is normal.
28. In combination, a railway track, a vehicle thereon, ramps on said track, a shoe carried by said vehicle and engaging said ramps, said shoe consisting of a horizontal and a vertical arm, a train controlling mechanism including a plunger, said plunger 85 biased to a certain position and maintained in a position opposed to said bias by said vertical arm when said shoe is not in engagement with said ramps.
29. In combination, a railway track, a vehicle thereon, ramps on said track, a shoe carried by said vehicle and engaging said ramps, said shoe comprising a weighted horizontal member, a train controlling mechanism biased to a position to retard the 90 progress of said train, said weighted member maintaining said mechanism in a position opposed to said bias normally and said mechanism being released when said shoe engages a ramp.
30. In combination, a railway track, a vehicle thereon, ramps on said track, a train controlling mechanism, a shoe carried by said vehicle for operating said train controlling mechanism, said shoe embodying a hori- 95

- zontal member engaging said ramps, and an operating member and means for adjusting the relation between said horizontal member and said ramps, and independent 5 means for adjusting the relation between said horizontal member and said operating member.
31. In combination, a railway track, a vehicle thereon, ramps on said track, a shoe 10 carried by said vehicle and displaced by said ramps, a fluid pressure timing device consisting of a plurality of chambers and a valve mechanism, said valve mechanism operated by said shoe and means governed 15 by said valve mechanism for quickly releasing the pressure in one of said chambers and gradually increasing it in another of said chambers when said shoe engages said ramps.
32. In combination, a railway track, a vehicle thereon, ramps on said track, a shoe 20 carried by said vehicle and engaging said ramps, a fluid pressure timing device comprising a plurality of chambers and a valve 25 mechanism, said valve mechanism operated by said shoe and means manually adjusted for varying the time interval of said device by varying the size of one of said chambers.
33. In combination, a railway track, a vehicle thereon, ramps on said track, a shoe 30 carried by said vehicle and engaging said ramps, a fluid pressure braking system on said vehicle, a fluid pressure timing device comprising a plurality of chambers and a 35 valve mechanism, said valve mechanism operated by said shoe and means responding to the pressure of said braking system for varying the time interval of said device.
34. In combination, a railway track, a vehicle thereon, ramps on said track, a shoe 40 carried by said vehicle and engaging said ramps, a fluid pressure braking system on said vehicle, a fluid pressure timing device including a valve mechanism, said valve mechanism operated by said shoe and means responding to the pressure of said braking system for increasing the time interval of 45 said device proportionally as said braking pressure is decreased.
35. In combination, a railway track, a vehicle thereon, ramps on said track, a shoe 50 carried by said vehicle and engaging said ramps, a fluid pressure braking system on said vehicle, a fluid pressure timing device including a plurality of chambers and a valve 55 mechanism, said valve mechanism operated by said shoe, a cylinder connected with said braking pressure operating a piston for varying the size of one of said chambers 60 whereby the time interval of said device is affected.
36. In combination, a railway track, a vehicle thereon, ramps on said track, a shoe 65 carried by said vehicle and engaging said ramps, a fluid pressure timing device con-
- sisting of a plurality of chambers and a valve mechanism, each of said chambers provided with a piston, said pistons connected together, said valve mechanism operated by said shoe and means for quickly moving said pistons from normal position when a ramp is encountered and means for moving them back again after a time interval.
37. In combination, a railway track, a vehicle thereon, ramps on said track, a shoe 70 carried by said vehicle and engaging said ramps, a fluid pressure timing device comprising a plurality of chambers and a valve mechanism, said chambers provided with a piston, said valve mechanism operated by said shoe, another cylinder and piston operating a circuit controller and connected by fluid pressure to respond to said first mentioned piston.
38. In combination, a railway track, a vehicle thereon, ramps on said track, a shoe 75 carried by said vehicle and engaging said ramps, a fluid pressure timing device comprising a plurality of chambers and a valve mechanism, said valve mechanism operated by said shoe, means including said valve mechanism for venting one of said chambers through a large opening and for setting up a limited passage for fluid pressure to 80 another of said chambers.
39. In combination, a railway track, a vehicle thereon, ramps on said track, a shoe 85 carried by said vehicle and engaging said ramps, a fluid pressure timing device operated by said shoe, a circuit including a brake valve, means including said timing device for interrupting said circuit instantly when said shoe encounters a ramp and for restoring it after a predetermined interval 90 of time.
40. In combination, a railway track, a vehicle thereon, ramps on either side of said track placed an equal distance from the center line, a shoe on either side of said vehicle engaging said ramps, a relay responding to each shoe, a cab signal, said signal giving one indication when both of 95 said relays are energized, another indication when either one of said relays is energized and the other deenergized and still another indication when both of the said relays are deenergized.
41. In combination, a railway track, a vehicle thereon, ramps on either side of said track placed an equal distance from the center line, a shoe on either side of said vehicle engaging said ramps, a relay responding to each shoe, a cab signal, said signal giving a clear indication when both of said relays are 100 energized, a caution indication when either one of said relays is energized and the other deenergized and a stop indication when both are deenergized.
42. In combination, a railway track, a 105

vehicle thereon, ramps on either side of said track, a shoe on either side of said vehicle engaging said ramps, a relay responding to each shoe, a cab signal giving different indications, one indication of said signal being controlled through both of said relays when energized, in series; another indication controlled through both of said relays in multiple and another indication controlled 10 through both of said relays when deenergized, in series.

43. In combination, a track, a vehicle thereon, ramps on said track, a shoe carried on said vehicle and engaging said ramps, a braking system for said vehicle, a timing device operated by said shoe, and means for affecting the operation of said timing device by said braking system.

44. In combination, a track, a vehicle thereon, ramps on said track, a shoe carried on said vehicle and engaging said ramps, a braking system for said vehicle, a timing device operated by said shoe, and means for varying the interval of said timing device 25 manually and also by said braking system.

45. In combination, a track, a vehicle thereon, ramps on said track, a shoe carried on said vehicle and engaging said ramps, a braking system for said vehicle controlled by said timing device, and means for rendering said control ineffective when said shoe is in engagement with a ramp.

46. In combination, a railway track, a vehicle thereon, ramps on either side of said track, a shoe on either side of said vehicle engaging said ramps, a relay responding to each shoe, a circuit established on said vehicle when both of said relays are energized, 35 another circuit established when either one of said relays is energized and the other deenergized and still another circuit being established when both of said relays are deenergized.

47. In combination, a railway track, a vehicle thereon, ramps on either side of said track, a shoe on either side of said vehicle engaging said ramps, a relay responding to each shoe, a plurality of brake valves operating a braking system on said vehicle, one of said valves being controlled by said relays in series and the other controlled by said relays in multiple.

48. In combination, a railway track, a vehicle thereon, ramps on either side of said track, a shoe on either side of said vehicle engaging said ramps, a relay responding to each shoe, a service and an emergency brake valve on said vehicle, said service brake valve controlled by said relays in series and said emergency brake valve controlled by said relays in multiple.

49. In combination, a railway track, a vehicle thereon, ramps on either side of said track, a shoe on either side of said vehicle

engaging said ramps, a relay responding to each shoe, a cab signal giving various indications and controlled by said relays, a service and an emergency brake valve, said brake valves maintained closed when both 70 of said relays are energized and a clear signal displayed, said service brake valve opened when either of said relays are deenergized corresponding with a caution signal and said emergency brake valve opened 75 when both of said relays are deenergized corresponding with a stop signal.

50. In combination, a railway track, a vehicle thereon, ramps on either side of said track, a shoe on either side of said vehicle 80 engaging said ramps, a relay responding to each shoe, a service and an emergency brake valve, said brake valves being maintained closed when both of said relays are energized, said service brake valve being opened 85 when either of said relays are deenergized and said emergency brake valve being opened when both of said relays are deenergized.

51. In combination, a railway track, a vehicle thereon, ramps on either side of said track, a shoe on either side of said vehicle engaging said ramps, means responding to each shoe, a brake valve, said brake valve controlled by said means and by both of said 95 shoes.

52. In combination, a railway track, a vehicle thereon, ramps on either side of said track, a shoe on either side of said vehicle engaging said ramps, a relay responding to each shoe, a brake valve, said brake valve controlled in series by said relays and in series by said shoes and controlled in multiple by said relays and shoes.

53. In combination, a railway track, a vehicle thereon, ramps on either side of said track, a shoe on either side of said vehicle engaging said ramps, a relay responding to each shoe, a brake valve, said brake valve controlled in multiple circuit by said relays 105 110 and in multiple circuit by said shoes and controlled in multiple circuit by said relays and shoes.

54. In combination, a railway track, a vehicle thereon, ramps on either side of said track, a shoe on either side of said vehicle engaging said ramps, a relay responding to each shoe, a service and an emergency brake valve, said service brake valve controlled in series circuit by said relays and in series circuit by said shoes and in multiple circuit by said relays and shoes and said emergency brake magnet valve controlled in multiple circuit by said relays and in multiple circuit by said shoes and in multiple circuit by 115 120 125 said relays and shoes.

55. In combination, a railway track, a vehicle thereon, ramps on either side of said track, a shoe on either side of said vehicle engaging said ramps, a relay responding to 130

- each shoe, a timing device operated by each shoe, a brake valve, said brake valve controlled by both of said relays and by both of said timing devices.
- 5 56. In combination, a railway track, a vehicle thereon, ramps on either side of said track, a shoe on either side of said vehicle engaging said ramps, a relay responding to each shoe, a timing device operated by each shoe, a brake valve, said brake valve controlled in series circuit by said relays and in series circuit by said timing devices and in multiple circuit by said relays and said timing devices.
- 10 57. In combination, a railway track, a vehicle thereon, ramps on either side of said track, a shoe on either side of said vehicle engaging said ramps, a relay responding to each shoe, a brake valve, a timing device operated by each shoe, said brake valve controlled by said relays and means including said timing device for maintaining said brake valve closed independently of said relays after said shoe has been a predetermined time in engagement with said ramp.
- 15 58. In combination, a railway track, a vehicle thereon, ramps on either side of said track, a shoe on either side of said vehicle engaging said ramps, a timing device operated by each shoe, means responding to said shoes, a brake valve controlled by said means and means including said timing device for maintaining said brake valve closed independently of said first mentioned means when either shoe has engaged said ramps for a predetermined time.
- 20 59. In combination, a railway track, a vehicle thereon, ramps on either side of said track, a shoe on either side of said vehicle engaging said ramps, a relay responding to each shoe, a timing device operated by each shoe, a brake valve released to apply the brakes, said brake valve released when either of said relays are deenergized and means preventing it from releasing when either of said shoes has engaged said ramps for a predetermined time.
- 25 60. In combination, a railway track, a vehicle thereon, ramps on either side of said track, a shoe on either side of said vehicle engaging said ramps, a relay responding to each shoe, a brake valve released to apply the brakes, said brake valve released when either of said relays are deenergized and means preventing it from releasing when either shoe is in engagement with said ramps.
- 30 61. In combination, a railway track, a vehicle thereon, ramps on either side of said track, a shoe on either side of said vehicle engaging said ramps, a relay responding to each shoe, a service and an emergency brake valve, said brake valves controlled by said relays and said shoes and means for applying said service brake when either shoe engages a ramp and means for applying said emergency brake when both shoes engage ramps simultaneously.
- 35 62. In combination, a railway track, a vehicle thereon, ramps on either side of said track, a shoe on either side of said vehicle engaging said ramps, a relay responding to each shoe, a brake valve, means for maintaining said brake valve closed when either of said relays are energized.
- 40 63. In combination, a railway track, a vehicle thereon, ramps on either side of said track, a shoe on either side of said vehicle engaging said ramps, a relay responding to each shoe, a brake valve, said brake valve controlled by said relays and by said shoes and means for maintaining said brake valve closed when either of said shoes are in engagement with said ramps.
- 45 64. In combination, a railway track, a vehicle thereon, ramps on either side of said track, a shoe on either side of said vehicle engaging said ramps, a brake valve, said brake valve controlled by said shoes and means for maintaining said brake valve closed when either of said shoes are in engagement with said ramps.
- 50 65. In combination, a railway track, a vehicle thereon, ramps on either side of said track, a shoe on either side of said vehicle engaging said ramps, a brake valve, said brake valve controlled by said shoes and means for opening said brake valve when both of said shoes engage ramps simultaneously.
- 55 66. In combination, a railway track, a vehicle thereon, ramps on either side of said track, a shoe on either side of said vehicle engaging said ramps, a relay responding to each shoe, a service and an emergency brake valve, said brake valves controlled by said relays and said shoes and means for applying said service brake when either shoe engages a ramp and means for applying said emergency brake when both shoes engage ramps simultaneously.
- 60 67. In combination, a railway track, a vehicle thereon, ramps on either side of said track, a shoe on either side of said vehicle engaging said ramps, a service and emergency brake valve released to apply the brakes, said brake valves controlled by said shoes and means for releasing said service brake valve when either shoe engages a ramp and means for releasing said emergency brake valve when both shoes engage ramps simultaneously.
- 65 68. In combination, a railway track, a vehicle thereon, ramps on either side of said track, a shoe on either side of said vehicle engaging said ramps, a timing device operated by said shoes, a service and an emergency brake valve released to apply the brakes, said brake valves controlled by said shoes and said service brake valve controlled by said timing devices, means for releasing

said service brake valve, subject to said timing devices, when either shoe engages a ramp and means for releasing said emergency brake valve when both shoes engage 5 said ramps.

69. In combination, a railway track, a vehicle thereon, ramps on said track, a shoe on said vehicle engaging said ramps, a brake valve controlling a braking system operated 10 by said shoe, a device for rendering said brake valve inoperative, means remotely located on said vehicle simultaneously and co-operatively affecting said device for rendering said brake valve inoperative.

15 70. In combination, a railway track, a vehicle thereon, ramps on said track, a shoe on said vehicle engaging said ramps, a brake valve controlling a braking system operated by said shoe, a relay when energized rendering said brake valve inoperative, switches 20 remotely located on said vehicle arranged when moved co-operatively to energize said relay and when moved non-co-operatively to deenergize it.

25 71. In combination, a railway track, a vehicle thereon, ramps on said track, a shoe on said vehicle engaging said ramps, a brake valve controlling a braking system operated by said shoe, means for rendering said brake 30 valve inoperative, devices remotely located on said vehicle co-operatively positioned for operating said means whereby said brake valve is rendered inoperative.

72. In combination, a track, a vehicle 35 thereon, ramps on either side of said track, a shoe on either side of said vehicle engaging said ramps, a brake valve, means responsive to each shoe arranged to control said brake valve, either of said means maintaining said 40 brake valve closed when energized.

73. In combination, a railway track, a vehicle thereon, ramps disposed at intervals on said track of various lengths, a shoe carried by said 45 vehicle and displaced by said ramps, a timing device operated by said shoe, said timing device affecting the control of said vehicle in accordance with the length of said ramps.

74. In combination, a railway track, a vehicle thereon, ramps on said track, a controlling mechanism, a shoe carried by said vehicle and displaced by said ramps, said shoe operating said controlling mechanism, a detector mechanism operated by the movement of said shoe, said mechanism arranged 55 to detect irregularities in said displacement.

75. In combination, a railway track, a vehicle thereon, ramps on either side of said track placed an equal distance from the 60 center line, a shoe on either side of said vehicle engaging said ramps, a cab signal, means responsive to each shoe and to current in said ramps, said means operating said cab signal in one position when both of said 65 ramps are energized and in another position

when either one is energized and the other deenergized.

76. In combination, a railway track, a vehicle thereon, ramps on either side of said track, a shoe on either side of said vehicle 70 engaging said ramps, a train controlling mechanism, means responsive to each shoe and to current in said ramps, said means varying the operation of said train controlling mechanism when both of said ramps 75 are energized, when either one is energized and the other deenergized and when both are deenergized.

77. In combination, a railway track, a vehicle thereon, ramps on either side of said track, a shoe on either side of said vehicle 80 engaging said ramps, a plurality of brake valves, said shoes controlling one of said brake valves in multiple circuit and controlling another of said brake valves in series circuit.

78. In combination, a railway track, a vehicle thereon, ramps on said track energized by a source of alternating current, a shoe on said vehicle engaging said ramps, a closed 90 circuit energized by direct current on said vehicle and interrupted by said shoe, an alternating current relay responding to the current in said ramps, said relay when energized, closing the circuit interrupted by 95 said shoe.

79. In a railway system, a track arranged for traffic in both directions, a separate set of ramps for each direction of traffic, a block system including means for directional control, said ramps spaced in said blocks and of decreasing length in the direction of traffic, a train, a shoe engaging said ramps, a train controlling mechanism operated by said shoe, the set of said ramps for the 100 established direction of traffic controlled by said block system, the other set of ramps energized by said directional control means, said train controlling mechanism responding to the length of said block controlled ramps. 110

80. In a railway system, a track, a train, a shoe on either side of said train, a train controlling mechanism, a block system, ramps on said track engaged by said shoes, certain of said ramps controlled by said block system and other ramps not controlled, said ramps placed in spaced relation to each other and operating said train controlling mechanism. 115

81. In a railway system, a track, a train, a shoe on either side of said train, a train controlling mechanism, a block system, ramps on said track engaged by said shoes, certain of said ramps controlled by said block system, other ramps not controlled, placed in 120 spaced relation to said controlled ramps and arranged to precede them in engaging said shoes, said ramps operating said train controlling mechanism.

82. In a railway system, a track arranged 125

for traffic in both directions, a train, a shoe, a train controlling mechanism, a block system, a separate set of ramps on said track for each direction of traffic, the set for the 5 established direction controlled by said block system and means for maintaining the other set energized, said ramps operating said train controlling mechanism.

83. In a railway system, a track arranged 10 for traffic in both directions, a train, a shoe, a train controlling mechanism, a block system, a separate set of ramps on said track for each direction of traffic, the ramps of each set placed in spaced relation to each 15 other, the set for the established direction controlled by said block system and means for maintaining the other set energized, the latter arranged to precede the former in engaging said shoes, said ramps operating 20 said train controlling mechanism.

84. In a railway system, a track, a train, ramps on either side of said track placed an equal distance from the center line, a shoe on either side of said train engaging said 25 ramps, a block system, said ramps controlled by said block system, a relay responding to each shoe and to the current in said ramps, signaling apparatus on said train having a plurality of operating circuits, said relays controlling one of said circuits in series, another of said circuits being operated when either one of said relays is energized and the other deenergized. 30

85. In a railway system, a track, a train, ramps on either side of said track placed an equal distance from the center line, a shoe on either side of said train engaging said ramps, a block system controlling one of said ramps through one block and another of 40 said ramps through two blocks, a relay responding to each shoe and to the current in said ramps, a signaling device, said device giving a clear indication when both of said relays are energized, a caution indication 45 when either of said relays are energized and the other deenergized and a stop indication when both of said relays are deenergized.

86. In a railway system, a track, a train, ramps on either side of said track placed an 50 equal distance from the center line, a shoe on either side of said train engaging said ramps, a block system controlling said ramps in accordance with the portion of track that is clear, means responding to said block system, a signaling device controlled by said means, said device responding to said block system without regard to the order in which said shoes engage said ramps. 55

87. In a railway system, a track, a train, 60 ramps on either side of said track placed an equal distance from the center line, a shoe on either side of said train engaging said ramps, a block system controlling one of said ramps through a home block and 65 the other through a distant block, a signal-

ing device, said signaling device differentiating the effects from said ramps without regard to which shoe engages either ramp.

88. In a railway system, a track, a train, ramps on said track having various characteristics and placed in spaced relation, a shoe engaging said ramps, a block system controlling said ramps according to traffic conditions, some of said ramps also controlled according to track conditions, a device on said train responsive to said characteristics and means including said device for controlling the speed of said train in accordance with traffic conditions and in accordance with track conditions. 70 75 80

89. In a railway system, a track, a train, ramps on either side of said track placed an equal distance from the center line, a shoe on either side of said train engaging said ramps, a block system controlling electric energy to said ramps, a relay responding to each shoe and to the current from said ramps, a device controlled by said relays, the control from either relay, when energized, being accumulative on that of the other and, when deenergized, being deductive from that of both. 85 90

90. In a railway system, a track arranged for traffic in both directions, a separate set of ramps for each direction of traffic, a block 95 system including means for directional control, said ramps spaced in said blocks and having various characteristics, a train, a shoe engaging said ramps, a train controlling mechanism operated by said shoe, the set of said ramps for the established direction of traffic controlled by said block system, the other set of ramps controlled by said directional control means, said train controlling mechanism responding to the 100 characteristics of said block controlled ramps. 105

91. In a railway system, a track, a train, ramps on either side of said track placed an equal distance from the center line, a shoe on either side of said train engaging said ramps, a block system controlling electric energy to said ramps in accordance with the portion of track that is clear, a relay 110 responding to each shoe and to the current from said ramps, a signaling device controlled by said relays and indicating the portion of track that is clear, said device responding to said relays without regard to the order in which they are operated. 115 120

92. In a railway system, a track, a train, ramps on either side of said track placed an equal distance from the center line, a shoe on either side of said train engaging said ramps, a block system controlling electric energy to said ramps in accordance with the portion of track that is clear, relays responding to the current in said ramps through each shoe, a brake valve controlled independently by each relay and means for 125 130

operating said valve when said track is not clear.

93. In a railway system, a track, a train, ramps on either side of said track placed an equal distance from the center line, a shoe on either side of said train engaging said ramps, a block system controlling one of said ramps through one block and the other through two blocks, a relay responding to each shoe and to said ramps as controlled by said block system, a service and an emergency brake valve, said brake valves controlled by said relays and means for operating said service brake valve when one block is clear and for operating both brake valves when neither block is clear.

94. In a railway system, a track, a train, ramps on either side of said track placed an equal distance from the center line, a shoe on either side of said train engaging said ramps, a block system controlling said ramps in accordance with the portion of track that is clear, means on said train responding to said block system, a service and an emergency brake valve, means for operating said service brake valve when said ramps are in staggered relation and a limited portion of track is clear and means for operating said emergency brake valve when said ramps are opposite and said track blocked.

95. The combination, a track, a train, ramps on either side of said track placed an equal distance from the center line, a shoe on either side of said train engaging said ramps, a block system controlling said ramps, a relay responding to each shoe and to said block system, a service and an emergency brake valve, said brake valves controlled by said relays and means for differentiating the operation of said brake valves by varying the relation of said ramps to each other.

96. The combination, a track, a train, ramps on either side of said track placed an equal distance from the center line, a shoe on either side of said train engaging said ramps, a block system controlling said ramps according to traffic conditions, a relay responding to each shoe and to said block system, a service and an emergency brake valve, said brake valves controlled by said relays, said service brake valve operated when the block is occupied and means for preventing the operation of said emergency brake valve by staggering the relation of said ramps to each other.

97. The combination, a track, a train, ramps on either side of said track placed an equal distance from the center line, a shoe on either side of said train engaging said ramps, a block system controlling said ramps according to traffic conditions, a relay responding to each shoe and to said block system, a service and an emergency brake valve,

said brake valves controlled by said relays, and by said shoes, and means for varying their operation by varying the arrangement of said track ramps.

98. In a railway system, a track, a train, ramps on either side of said track placed an equal distance from the center line, a shoe on each side of said train engaging said ramps, a block system controlling said ramps in accordance with traffic conditions, a cab signal responding to said shoes and to said block system, a braking system giving various braking effects, means for preventing the operation of said braking system when said cab signal is clear and means for varying the braking effects by the arrangement of said ramps when said cab signal is not clear.

99. In a railway system, a track, a train, ramps on either side of said track, a shoe on each side of said train engaging said ramps, a block system controlling said ramps in accordance with traffic conditions, a braking system giving various braking effects and controlled by said block system, means for varying the braking effect in accordance with said traffic conditions by varying the relation of said ramps to each other.

100. In a railway system, a track, a train, ramps on either side of said track, a shoe engaging said ramps, a block system dividing said track into blocks and arranged for traffic in both directions, said ramps controlled by said block system, a section of track opposite said ramps and means for transferring the block control of said section in accordance with the established direction of traffic whereby said ramps are engaged before said train enters the block through which they are controlled.

101. In a railway system, a track, a train, ramps on either side of said track, a shoe on either side of said train engaging said ramps, a block system dividing said track into blocks and including directional control relays for establishing the direction of traffic, said ramps controlled by said block system, a device on said train responding to said block system, a section of track opposite said ramps, said directional control relays making the block control of said ramps effective in the following section for the established direction of traffic.

102. In a railway system, a track, a train, ramps on said track, a shoe engaging said ramps, a block system dividing said track into blocks and including directional control relays for establishing the direction of traffic, said ramps controlled by said block system, a device on said train responding to said block system, a section of track opposite said ramps, said directional control relays including said section in the block toward approaching traffic.

103. In a railway system, a track, a train,

ramps on said track, a shoe engaging said ramps, a block system including track circuits and means for establishing the direction of traffic, said ramps controlled by said block system, a device on said train responding to said block system, a section of track opposite said ramps, said means for establishing the direction of traffic controlling said ramps through the adjacent track circuits according to the established direction of traffic.

104. In a railway system, a track, a train, ramps on either side of said track, a shoe on either side of said train engaging said ramps, a block system controlling said ramps according to traffic conditions, a timing device operated by each shoe, a train controlling mechanism, said ramps spaced in said blocks and progressively of shorter length and means including said timing device for mechanically controlling the speed of said train progressively through said blocks.

105. In a railway system, a track, a train, ramps on either side of said track, a shoe on either side of said train engaging said ramps, a block system controlling said ramps according to traffic conditions, a timing device operated by each shoe, a train controlling mechanism, said ramps spaced in said blocks and progressively of shorter length and means including said timing device for progressively controlling the speed of said train according to traffic conditions without regard to which shoe engages said ramps.

106. In a railway system, a track, a train, ramps on either side of said track, a shoe on either side of said train engaging said ramps, a block system controlling some of said ramps according to traffic conditions, a timing device operated by each shoe, a train controlling mechanism controlled by said timing devices, said ramps spaced in said blocks and of various lengths and means including said timing device for controlling the speed of said train in accordance with the length of said ramps.

107. In a railway system, a track, a train, ramps on said track, a shoe on said train engaging said ramps, a block system controlling some of said ramps according to traffic conditions, a timing device operated by said shoe, a train controlling mechanism controlled by said timing device, said ramps of various lengths, the block controlled ramps spaced with relation to said blocks, the other ramps spaced without relation to said block system and means including said timing device for controlling the speed of said train in accordance with the length of said ramps.

108. In a railway system, a track, a train, ramps on said track, a shoe on said train engaging said ramps, a block system controlling some of said ramps according to traffic

conditions, a timing device operated by said shoe, a train controlling mechanism controlled by said timing device, the ramps controlled by said block system being spaced in said blocks and progressively of shorter length, other ramps of various lengths spaced with relation to track conditions, each of the latter ramps placed adjacent to one of the former ramps and means including said timing device for controlling the speed of said train in accordance with the length of said ramps.

109. In a railway system, a track, a train, ramps on said track, a shoe on said train engaging said ramps, a block system controlling some of said ramps according to traffic conditions, other of said ramps controlled according to track conditions, a timing device operated by said shoe, a train controlling mechanism controlled by said timing device, said ramps of various lengths and placed in spaced relation on said track, means including said timing device for controlling the speed of said train in accordance with traffic conditions and in accordance with track conditions.

110. In a railway system, a track, a train, ramps on said track, a shoe on said train engaging said ramps, a block system controlling some of said ramps according to traffic conditions, other of said ramps controlled according to variable track conditions, a timing device operated by said shoe, a train controlling mechanism controlled by said timing device, said ramps of various lengths and placed in spaced relation on said track, means including said timing device for controlling the speed of said train in accordance with traffic conditions and in accordance with said variable track conditions.

111. In a railway system, a track, a train, ramps on said track, a shoe on said train engaging said ramps, a block system controlling some of said ramps according to traffic conditions, a switch on said track, said switch controlling other of said ramps according to its position a timing device operated by said shoe, a train controlling mechanism controlled by said timing device, said ramps of various lengths and placed in spaced relation on said track, means including said timing device for controlling the speed of said train in accordance with traffic conditions and in accordance with the position of said switch.

112. In a railway system, a track, a train, ramps on said track, a shoe on said train engaging said ramps, a block system including directional control relays for establishing the direction of traffic, said ramps controlled by said block system, a timing device operated by said shoe, a train controlling mechanism controlled by said timing device, a separate set of ramps for each direction of

traffic said ramps spaced on said track and progressively of shorter length in the direction of traffic and means including said timing device for controlling the speed of said train in either direction according to traffic conditions.

113. In a railway system, a track, a train, ramps on said track, a shoe on said train engaging said ramps, a block system including directional control relays for establishing the direction of traffic, a separate set of ramps for each direction of traffic, one set of ramps controlled by said block system according to traffic conditions, the other set of ramps energized by said directional control relays, a timing device operated by said shoe, a train controlling mechanism controlled by said timing device, said ramps spaced on said track, one ramp of each set being located adjacent to a ramp of the other set, said ramps of various lengths and means including said timing device for controlling the speed of said train in accordance with traffic conditions.

114. In a railway system, a track, a train, ramps on said track, a shoe on said train engaging said ramps, a block system including directional control relays for establishing the direction of traffic, a separate set of ramps for each direction of traffic, one set of ramps controlled by said block system according to traffic conditions, the other set of ramps energized by said directional control relays according to the established direction of traffic, a timing device operated by said shoe, a train controlling mechanism controlled by said timing device, a device on said train responding to the energy in said ramps, said ramps of various length and spaced on said track and means including said timing device for controlling the speed of said train in the established direction according to traffic conditions.

115. In a railway system, a track, a train, a separate set of ramps for each direction of traffic on said track, a block system including directional control relays for establishing the direction of traffic, the set of ramps for the established direction of traffic controlled by said block system according to traffic conditions, a timing device operated by said shoe, a train controlling mechanism controlled by said timing device, a device on the train also controlling said train controlling mechanism, said ramps of various lengths and spaced on said track and means including said timing device for controlling the speed of the train by said block controlled ramps and means including said directional control relays and said device for rendering the set of ramps for the opposing direction of traffic ineffective in controlling the speed of said train.

116. In a railway system, a track, a loco-

motive, devices disposed at intervals on either side of said track, means on each side of said locomotive coacting with said track devices, a mechanism on said locomotive responsive to said track devices through said means, said mechanism differentiating the effects when one track device is encountered, when a track device is encountered on each side of said track, when two track devices are encountered simultaneously, when said track devices are energized and when they are deenergized.

117. In a railway traffic controlling system, a track, a locomotive, devices disposed at intervals on either side of said track an equal distance from the center line, means on each side of said locomotive coacting with said track devices, a device on said locomotive responding to said track devices through said means, said device being operated similarly but independently by the means on either side of said track.

118. In a railway traffic controlling system, a track, a locomotive, devices disposed at intervals on either side of said track an equal distance from the center line, means on each side of said locomotive coacting with said track devices, a device on said locomotive responding to said track devices through said means, the operation of said device by the means on either side of said locomotive being accumulative on a similar operation by the means on the other side.

119. In a railway traffic controlling system, a track, a locomotive, devices disposed at intervals on either side of said track an equal distance from the center line, means on each side of said locomotive coacting with said track devices, a device on said locomotive responding independently to the devices on each side of said track through said means, the operation of said device by the means on either side of said locomotive being canceled by an operation of the means on the other side.

120. In a railway traffic controlling system, a track, a locomotive, devices disposed at intervals on either side of said track, means on each side of said locomotive coacting with said track devices, a device on said locomotive responding independently to the devices on each side of said track through said means, the operation of said device by the means on either side of said locomotive being accumulative or deductive as affecting the operation by the means on the other side.

121. In a railway traffic controlling system, a track, a locomotive, devices disposed at intervals on either side of said track, means on each side of said locomotive coacting with said track devices, a plurality of devices on said locomotive responding to the devices on each side of said track through said means, one of said devices being oper-

ated by the means on either side of said locomotive and the other device being operated by both of said means simultaneously.

122. In a railway traffic controlling system, a track, a locomotive, devices disposed at intervals on either side of said track, means on each side of said locomotive coacting with said track devices, a plurality of devices on said locomotive responding to the 5 devices on each side of said track through said means, one of said devices being operated when said track devices on either side of the track are in staggered relation to each other and both of said devices being operated 10 when said track devices are placed opposite.

123. In a railway traffic controlling system, a track, a locomotive, devices of different characteristics disposed at intervals on either side of said track, means on each side 20 of said locomotive coacting with said track devices, a cab signal, a braking system, said cab signal responding to said track devices through said means, said braking system operated by said means and means for varying 25 the effect of said braking system under a caution signal by varying the characteristic of said track devices.

124. In a railway traffic controlling system, a track, a locomotive, devices disposed 30 at intervals on either side of said track, a block system, said block system controlling said track devices according to traffic conditions, a service and an emergency braking system, means on each side of said locomotive 35 coacting with said track devices, a cab signal responding to said block system, means for operating said service braking system when said signal is not clear and means for operating said emergency braking 40 system according to the arrangement of said track devices when said signal is not clear.

125. In a railway traffic controlling system, a track, a locomotive, devices disposed 45 at intervals on either side of said track an equal distance from the center line, a block system controlling one of said devices through one portion of track and the device on the opposite side of the track 50 through a greater portion of track, means on each side of said locomotive coacting with said track devices, a cab signal responding independently to each of said means and indicating the amount of track that is clear 55 according to said block system.

126. In a railway system, a train, a track, devices disposed at intervals on either side of said track, means on each side of said locomotive engaging said devices, a mechanism 60 responding to said track devices, and means for varying the operation of said mechanism when the devices on either side of said track are engaged at the same and at different times.

127. In a railway traffic controlling system, a track, a locomotive, devices disposed at intervals on either side of said track, a block system, said block system controlling said devices according to traffic conditions, other devices disposed on said track with relation to the permissible speed, said devices having variable characteristics, a device on said locomotive responsive to said characteristics and means for controlling the speed of said locomotive in accordance with traffic 75 conditions and in accordance with the permissible speed.

128. In a railway traffic controlling system, a track, a locomotive, devices disposed at intervals on said track, a block system, 80 said block system controlling said devices in accordance with traffic conditions, limited speed sections on said track, other devices located with relation to said limited speed sections, said devices having variable characteristics, a device on said locomotive responsive to said characteristics and means for controlling the speed of said locomotive independently and without regard to any previous condition in accordance with traffic 90 conditions and in accordance with said limited speed.

129. In a railway traffic controlling system, a track, a locomotive, devices disposed at intervals on said track, said devices having variable characteristics, means on said locomotive coacting with said devices, a device on said locomotive operated by said means and responsive to said characteristics, a braking system on said locomotive, said 95 device also responsive to said braking system and means for controlling the speed of said locomotive in accordance with said track devices and in accordance with said braking system.

130. In a railway traffic controlling system, a track, a locomotive, devices disposed at intervals on said track with relation to speed and having variable characteristics, means on said locomotive coacting with said 110 devices, a device on said locomotive operated by said means, a mechanism on said locomotive, said device responsive to said mechanism and to the characteristics of said devices and means for controlling the speed of 115 said locomotive without regard to any previous condition in accordance with the allowable speed on said track and in accordance with said mechanism.

131. In a railway traffic controlling system, a track, a locomotive, devices disposed on said track on the same plane relative to the center line, a block system, said block system controlling said devices according to traffic conditions, other devices arranged on 125 said track according to track conditions, said devices having variable characteristics, a mechanism on said locomotive, a device on

5 said locomotive, said device responsive to the characteristic of said track devices and to said mechanism, means for controlling said locomotive in accordance with the conditions affecting traffic, the track and the locomotive.

132. In a railway traffic controlling system, a track, a locomotive, devices disposed on said track, a block system, said block system 10 controlling said devices in accordance with traffic conditions, a signal device responding to said block system and giving an unchanged signal for unchanged traffic conditions, a timing device responding to said 15 devices on said track, said timing device limiting the effectiveness of said signal device.

133. In a railway traffic controlling system, a track, a locomotive, devices disposed on said track, a block system arranged for 20 traffic in both directions and controlling said devices in accordance with traffic conditions, said devices having various characteristics, a signal on said locomotive responding to said block system and a device responding to 25 the characteristic of said track devices and means including said device for controlling the speed of said locomotive in both directions in accordance with traffic conditions.

134. In a railway traffic controlling system, a track, a locomotive, a block system 30 arranged for traffic in both directions, a separate set of devices disposed on said track for traffic in each direction, said devices controlled by said block system and having various characteristics, a speed control device on said locomotive responding to said 35 characteristics and controlling its speed in accordance with traffic conditions for the established direction of traffic and means for rendering the devices disposed on said track 40 for the opposite direction of traffic ineffective in controlling the speed of said locomotive.

135. In a railway traffic controlling sys-

tem, a track, a locomotive, devices disposed 45 on either side of said track having variable characteristics, means on each side of said locomotive coacting with said devices, a speed control device responding to said characteristics through said means and means for 50 determining the allowable speed at any particular location on said track.

136. In a railway traffic controlling system, a track arranged for traffic in both directions, a locomotive running either end 55 first, devices disposed on either side of said track, means on each side of said locomotive coacting with said devices, a block system, said block system controlling said devices in accordance with traffic conditions, a device 60 on said locomotive responding through said means to said block system, said device without change in the arrangement of its control registering traffic conditions without regard to the direction of traffic and without 65 regard to the end of said locomotive that is running first.

137. In a railway traffic controlling system, a track, a locomotive running either end first, devices disposed on either side of said 70 track, means on each side of said locomotive coacting with said devices, a block system, said block system controlling said devices through various portions of track in accordance with traffic conditions, a device on said 75 locomotive responding through said means to said block system, said device without change in the arrangement of its control registering traffic conditions without regard to which end of said locomotive is running 80 first.

In testimony whereof I have signed my name in the presence of two witnesses.

MATTHEW H. LOUGHBRIDGE.
